(57) **CLAIM**

We claim an ornamental design for a bottle, as shown and described.

DESCRIPTION

FIG. 1 is a perspective view of a bottle in accordance with the present invention;

FIG. 2 is a front elevation view thereof, the left side, right side and rear elevation views being identical; and,
FIG. 3 is a top plan view thereof.

The broken lines in the drawings illustrate the portions of the bottle that form no part of the claim.
